LIGHTING FIXTURE SUPPORT

Daniel Fekete, North Hills, Pa., assignor to Progress Manufacturing Company, Inc., Philadelphia, Pa., a corporation of Pennsylvania

Application April 2, 1956, Serial No. 575,520

5 Claims. (Cl. 240—146)

This invention relates generally to ceiling type electric light fixtures and more particularly to improved means for mounting the shade of such a fixture.

A principal object of the present invention is to provide means for suspending the shade of a ceiling type electric light fixture whereby used electric light bulbs can be conveniently replaced with a minimum expenditure of time and effort.

Other objects and advantages of the present invention will appear more fully hereinafter, it being understood that the invention consists substantially in the combination, construction, location and relative arrangement of parts, all as described in the accompanying drawings and as finally pointed out in the appended claims.

In the accompanying drawings:

Figure 1 is a vertical section taken through a ceiling type electric light fixture constructed in accordance with and embodying the principals of the present invention;

Figure 2 is the same as Figure 1, however, the shade has been dropped to facilitate changing the electric light bulb;

Figure 3 is the same as Figure 2, however, the shade is shown canted toward one side;

Figure 4 is an enlarged section taken on line 4—4 of Figure 2;

Figure 5 is an enlarged section taken on line 5—5 of Figure 1; and

Figure 6 is a section on line 6—6 of Figure 4.

Referring particularly to Figure 1, the electric light fixture constructed in accordance with and embodying the principals of the present invention comprises a canopy 10 and an assembly 11 that depends from the canopy 10 and which has a glass bowl or shade 12 mounted upon the lower end thereof in underlying relation to an electric light bulb 13.

Referring particularly to Figure 5, it will be observed that the assembly 11 comprises an adapter sleeve 14 having a large diameter upper end portion 15 which is internally threaded and turned onto the lower extremity of a tubular member 16 secured to and depending from the canopy 10, as well as a small diameter lower end portion or nipple 17 which is externally threaded for receiving a cap nut 18. The shade 12 is centrally apertured and loosely fitted over the lower end portion 17 of the adapter sleeve 14. The bowl 12 rests directly upon a felt washer 19 that is located inside a decoratively dished washer 20, and just above the base wall of the bowl 12 is a second felt washer 19. The cap nut 18 is threaded onto the adapter sleeve 14 a distance sufficient for clamping the washers 19—19 and 20 and the shade 12 between the cap nut 18 and an annular shoulder 21 that is formed on the underside of the upper end portion 15 of the adapter sleeve 14.

Threaded into the crown of the cap nut 18 is the lower end portion of a rigid rod 22 that extends upwardly freely through the adapter sleeve 14 and into the tubular member 16, terminating in a free end portion which is pro-

2

vided with a pair of lateral protuberances 23—23 extending outwardly in opposite directions. This rod 22 is fixedly secured to the cap nut 18 for rotation therewith, the rod 22 being thus freely rotatable in the tubular member 16 upon turning the cap nut 18 in either direction.

Formed within the adapter sleeve 14 just below the lower end of the tubular member 16 is an internal flange 24 providing a restricted passage therethrough of a diameter substantially less than that of the tubular member and of the section of the passage through said adapter sleeve located below the flange 24, said passage being so reduced as to prevent complete separation of the rod 22 downwardly from the adapter sleeve 14 (see Figure 4).

Referring particularly to Figures 1 and 5, when it becomes necessary to replace the electric light bulb 13 or to clean the interior of the shade 12, it is only required to unscrew the cap nut 18, whereupon the assembly comprising the cap nut 18, the rigid rod 22, the washers 19—19 and 20 and the shade 12 may be lowered as a unit to the position shown in Figures 2 and 4, wherein the protuberances 23—23 provided on the upper end of the rod 22 are seated upon the annular formation 24 within the adapter sleeve 14. It will be appreciated that with the shade suspended in the manner described at an increased distance from the canopy, sufficient access is provided between the shade and the canopy for convenient removal and replacement of the light bulb 13 and for cleaning the internal surface of the shade.

It will be noted that even greater access may be had to the interior of the shade by simply tilting the suspended assembly as shown in Figure 3. In performing these operations, the shade remains safely suspended from the canopy and is readily replaced in secure position by shifting it vertically into its normal position shown in Figure 1 to permit re-engagement of the cap screw 18 with the threaded nipple 17 of the adapter sleeve 14.

It will be understood, of course, that the present invention as hereinbefore described and shown in the accompanying drawings is susceptible of various changes and modifications which may be made from time to time without departing from the general principles or real spirit of the invention, and accordingly, it is intended to claim the same broadly, as well as specifically, as indicated by the appended claims.

What is claimed as new and useful is:

1. In a device for mounting the shade of a ceiling type electric light fixture, a tubular member, an elongated rigid element freely projected into one end of said member, means securing corresponding end portions of said tubular member and rigid element together, an electric light shade seated upon said securing means, said securing means being detachable from said tubular member, and the assembly including said securing means, rigid element and shade being thereupon shiftable as a unit into axial extension of said tubular member, and means securing said tubular member and rigid element against disassembly and thereby limiting the movement aforesaid of said assembly relative to said tubular member.

2. In a device for mounting the shade of a ceiling type electric light fixture, a tubular member, an adapter sleeve fitted over one end portion of said tubular member and having a circumferentially extending external shoulder intermediate the opposite ends thereof, a cap element fitted over a reduced diameter end portion of said adapter sleeve, a rigid rod fixedly secured to said cap element and freely projected through said adapter sleeve and into said tubular member, an electric light shade seated upon said cap element and clamped thereby against said adapter shoulder, said cap element being de-

tachable from said adapter sleeve, and the assembly including said cap element, rigid rod and shade being thereupon shiftable as a unit into axial extension of said tubular member and adapter sleeve, and means securing said tubular member and rigid element against disassembly and thereby limiting the movement aforesaid of said assembly relative to said tubular member and adapter sleeve.

3. In a device for mounting the shade of a ceiling type electric light fixture as defined in claim 2 wherein the large diameter end portion of the adapter sleeve is fitted to the tubular member, the cap element is threaded onto the reduced diameter end portion of said adapter sleeve, said cap element and reduced diameter end portion of said adapter sleeve being disposed in longitudinal continuation of said tubular member.

4. In a device for mounting the shade of a ceiling type electric light fixture, a tubular member, an adapter sleeve having an end portion fitted over one end portion of said tubular member, and an opposite end portion extending in longitudinal continuation of said tubular member, at least a portion of said adapter beyond the end of said tubular member being provided with an internal diameter substantially smaller than that of said tubular member to thereby form an annular internal seat, a cap element fitted over the free end of said adapter sleeve, a rigid rod fixedly secured to said cap element and extending through said adapter sleeve and into said tubular member, the free end portion of said rod being laterally expanded to preclude withdrawal thereof through the small internal diameter portion of said adapter sleeve and for swinging movement of the lower end portion of said rod from side to side when said expanded free end portion of the rod is engaged with the annular internal seat aforesaid, an electric light shade seated upon said cap element, the latter being detachable from said adapter sleeve, and the assembly including said cap element, rigid rod and shade being thereupon shiftable within a predetermined range as a unit into axial extension of said tubular member and adapter sleeve and from side to side.

as a unit into axial extension of said tubular member and adapter sleeve and from side to side.

5. In a device for mounting the shade of a ceiling type electric light fixture, a tubular member, an adapter sleeve having an axially extending through passage and an annular formation intermediate the opposite ends of said sleeve extending radially into said passage to thereby restrict the size thereof and form an annular internal seat, an end portion of said adapter sleeve being fitted over one end portion of said tubular member and the opposite end portion of said adapter sleeve being disposed in longitudinal continuation of said tubular member, with said annular internal seat beyond the end of said tubular member, a cap element fitted over the free end of said adapter sleeve, a rigid rod fixedly secured to said cap element and extending through said adapter sleeve and into said tubular member, the free end portion of said rod being laterally expanded to preclude withdrawal thereof through said annular internal formation and for swinging movement of the lower end portion of said rod from side to side when said expanded free end portion of the rod is engaged with the annular internal seat aforesaid, an electric light shade seated upon said cap element, the latter being detachable from said adapter sleeve, and the assembly including said cap element, rigid rod and shade being thereupon shiftable within a predetermined range as a unit into axial extension of said tubular member and adapter sleeve and from side to side.
